MOBILE FAN HOUSING

Robert Podall, Chicago, Ill., assignor to Berns
Manufacturing Corporation, Chicago, Ill., a
corporation of Illinois

Application January 2, 1953, Serial No. 22,982

Term of patent 14 years

(Cl. D26—7)

To all whom it may concern:

Be it known that I, Robert Podall, a citizen of the United States of America and a resident of Chicago, Cook County, Illinois, have invented a new, original, and ornamental Design for a Mobile Fan Housing, of which the following is a specification, reference being had to the accompanying drawing, forming a part hereof.

Fig. 1 is a rear perspective of a mobile fan housing, showing my new design;

Fig. 2 is a side perspective of the same;

Fig. 3 is a frontal perspective view of the same.

The top is without ornamentation other than that shown in Figs. 1, 2, and 3.

The opposite side is identical to that shown in Fig. 2.

I claim:

The ornamental design for a mobile fan housing, as shown and described.
